UNITED STATES PATENT OFFICE.

WILLIAM O. BROWN, JR., OF TOLEDO, OHIO, ASSIGNOR OF ONE-HALF TO
J. H. HARVEY, OF SAME PLACE.

ENVELOP AND ENVELOP-FASTENER.

SPECIFICATION forming part of Letters Patent No. 663,327, dated December 4, 1900.

Application filed May 23, 1900. Serial No. 17,699. (No model.)

To all whom it may concern:

Be it known that I, WILLIAM O. BROWN, Jr., of Toledo, in the county of Lucas, State of Ohio, have invented certain new and useful 5 Improvements in Envelops and Envelop-Fasteners, of which the following is a complete specification, reference being had to the accompanying drawings.

The object of my invention is to produce 10 an improved envelop that is especially adapted to be used by aid of a special fastener as a receptacle for mail-matter for the transmission of which low rates of postage are charged, but of course without limiting the 15 device from any application to which it may be put.

In the accompanying drawings, Figure I is a side view of a portion of my envelop open with fastener attached thereto. Fig. II is a 20 similar view showing the mouth of the envelop partially folded for closing. Fig. III is a similar view showing the envelop completely folded, closed, and fastened. Fig. IV is a similar view showing a slightly-modified form 25 of my envelop-fastener. Fig. V is a perspective view of the fastener shown in Figs. I to III, inclusive. Fig. VI is a detail view of a further modification of the fastener.

Referring to the numerals on the drawings, 30 1 indicates the body of an envelop of any suitable shape and dimensions. As illustrated, it is shown as provided with overlaps 2, which are united by any suitable adhesive material, as in the ordinary manufacture of 35 paper bags or envelops. The envelop illustrated is of the variety which opens at one end. At that end the envelop is cut square across, as indicated, the edges 4 and 5 (see Fig. II) ending flush with each other. For 40 closing the envelop it is creased or otherwise adapted to be folded along the dotted lines 7, 8, and 9. (Shown in Fig. I.) When the envelop is folded along the lines 7, 8, and 9, it forms in effect a single flap, (designated 45 by the reference-numeral 11 in Fig. III,) and so effects a complete closure of the mouth of the envelop, so that if the flap be secured to the body of the envelop it may be relied upon to hold the contents of the envelop without 50 sealing.

In order to detachably fasten the end of

the flap 11 to the body of the envelop, I prefer to employ a fastener 14, consisting, essentially, of a strip of suitable material (preferably metal) provided with a longitudinal slit 15 55 for the reception of the end of the flap 11, a detent, and means for securing the fastener to the body of the envelop. The detent preferably consists of a neck 16 and an enlarged head 17 and is thereby adapted when inserted 60 in a perforation 18 in the flap 11 to secure the same. The means for securing the fastener to an envelop may be of any suitable kind. For example, they may be the tangs 19, (illustrated in detail in Fig. V,) and which 65 after insertion into the body of the envelop are bent underneath the fastener, or they may consist of eyelets 20. (Indicated in Fig. IV of the drawings.)

The perforation 18 is made in a thickness 70 of material which will afford ample resistance to the accidental tearing out of the detent from the flap 11. For this reason in connection with my fastener I prefer to employ the envelop illustrated, as affording three 75 thicknesses of material through which the perforation 18 is made. It is obvious, however, that my fastener is adapted to other forms of envelops and other forms of flaps thereon than those illustrated. 80

For convenience of manipulation the fastener is provided with a slightly-raised strip 21, (see Fig. V,) the strip 21 being that part of the fastener which carries the detent.

In Fig. VI, I illustrate a modification of the 85 fastener, which consists in omitting the slit 15 and the middle tang 19. This modification constitutes no departure in principle from the other forms of my fastener illustrated and but a slight departure in the form 90 thereof. The definition of the strip 21 by the slit 15 is merely intended to utilize a portion of the strip 14 to retain the flap 11. Through employment of the form of fastener shown in Fig. VI the whole body of the fastener instead of the strip thereof is utilized 95 to retain the flap of the envelop against the body of the envelop. In Fig. VI the numeral 23 indicates the strip of which the fastener is composed. It is provided with terminal 100 means of securing it to an envelop—for example, tangs 24. It is also provided with a

medial detent 25. The detent 25 is shown as wedge-shaped to enter a transverse slit in the flap 27 of the envelop; but this is a mere variation as to detail.

5 In practice the envelop having the flap 11 and provided with the fastener properly applied in required position to the body of the envelop is folded so as to bring the flap into operative reach of the fastener. The end of 10 the detent is slipped into the perforation 18 in the flap. In this position the flap is securely held by the detent and the head of the detent is covered and protected by the end of the flap. If the flap 11 be formed upon an 15 envelop of the preferred form illustrated, the corners of the envelop, in forming the flap by creasing the envelop down along the lines 7 and 9, are held down underneath the flap and are secured by the fold of the flap and 20 by its engagement with the fastener.

The operation of the device shown in Fig. VI is substantially as above described, except that the flap 27 is inserted under the fastener 23 instead of through a slit therein.

25 What I claim is—

1. The combination with an envelop provided with a flap, of a fastener consisting of a separate member secured to the body of the envelop provided with a slit and detent, and 30 means upon the flap for engaging the detent after the end of the flap is passed through the slit.

2. The combination with a square-cut envelop folded to form a flap, of a fastener secured to the body of the envelop, provided

with a slit and a detent, and means for engaging the flap after the end of the body part thereof is passed through the slit, substantially as set forth.

3. The combination with a square-cut envelop provided with a perforation near its upper end and folded to form a flap, of a fastener secured to the body of the envelop and provided with a slit and detent, the detent being adapted to enter the perforation in the 45 flap and secure the same after the end of the body part of the flap is passed through the slit, substantially as set forth.

4. As a new article of manufacture an envelop-fastener consisting of a strip adapted 50 to be secured to an envelop, and provided with a detent upon one side thereof, extending substantially in the plane of the strip.

5. An envelop-fastener consisting of a strip 55 adapted to be secured to an envelop, and provided with a single longitudinal slit, and a detent upon one side thereof, substantially as set forth.

6. An envelop-fastener consisting of a slit- 60 ed strip adapted to be secured to an envelop, and a raised strip defined by the slit therein, and a detent upon the outer edge of the raised strip, substantially as set forth.

In testimony of all which I have hereunto subscribed my name.

WILLIAM O. BROWN, JR.
